UNITED STATES PATENT OFFICE.

THEODOR NORPOTH, OF ST. LOUIS, MISSOURI, ASSIGNOR OF ONE-FOURTH TO T. G. EHRHARDT, OF CALIFORNIA, MISSOURI.

PLAYING-CARDS.

1,230,317.

Specification of Letters Patent. Patented June 19, 1917.

Application filed October 2, 1916. Serial No. 123,394.

To all whom it may concern:

Be it known that I, THEODOR NORPOTH, a citizen of the United States, residing at St. Louis, State of Missouri, have invented certain new and useful Improvements in Playing-Cards, of which the following is a full, clear, and exact description, reference being had to the accompanying drawings, forming a part thereof.

10 My invention has relation to improvements in playing cards, more particularly baseball playing cards, and consists in the novel features of denomination and arrangement more fully set forth in the specification and pointed out in the claims.

In the drawings Figure 1 represents one suit of a pack of cards marked according to my invention; Fig. 2 represents a card of a different suit, marked to correspond with 20 one play of a baseball game; and Fig. 3 represents a card marked to correspond with a different play in the game.

The object of my invention is to provide a pack of cards comprising a series of suits, 25 the suits representing different baseball teams, and each suit consisting of cards marked to correspond with some play possible in a game of baseball, the value of the card depending upon the corresponding 30 value of the play in a regular game. Some of the cards will also represent a certain player, as shown in Fig. 1, and will contain a supplemental marking indicating the play, said play being credited to the player represented by the card. The character of the 35 invention will best be understood from a detailed description thereof in connection with the accompanying drawings, in which—

1 represents one card of the suit corresponding to the St. Louis team. The card is similarly marked on both sides of a horizontal center line *a* (like ordinary playing cards) so that it may be read no matter which side is on top. The card 1 is marked 40 along both end margins with the word "Pitcher", and has a picture *p* of a baseball pitcher on both halves of the card in opposed relation. In the upper left-hand corner of the card, and in the corner diagonally opposite, are diamond-shaped figures *d*, *d*, in the center of which are letters "P", "P", the same being abbreviations of the word pitcher; beneath each diamond, arranged in a column and extending toward the center 45 of the card are the letters of the word "St. Louis", the particular team and suit. It is

apparent that placing the diamond containing the abbreviation of the name of the card in the left-hand corner and the name of the team represented thereby beneath it, the 60 cards may be held in fan-like formation, as shown, and still permit their denominations to be readily seen. The cards 2, 3, 4, 5, 6, 7, 8, 9 and 10 are marked "S3", "F", "B2", "S2", "E", "BH", "2", "3", and 65 "HR" respectively in the diamonds *d*, *d*, etc., these abbreviations standing for strike three, foul, ball two, strike two, error, base-hit, two base-hit, three base-hit, and home-run 70 respectively. All of the cards shown in Fig. 1 are similarly marked with the words "St. Louis", since they all belong to one suit and represent one team. Just as the card 1 has a picture of a pitcher on each half, so do the 75 other cards have pictures (not visible in Fig. 1) corresponding to the notation in the diamond *d*.

Fig. 2 represents a card 11 of a different suit, viz., that representing the Chicago 80 team and is so marked, all of the other markings being the same as a like card 10 of the St. Louis suit.

Fig. 3 represents a card 12 of the suit illustrated in Fig. 1, and is similar to the other 85 cards of the suit except that it corresponds to "ball four" in a ball game and is marked accordingly. It also has a picture of a baseball *b* instead of a player in each half of the card. Let it be understood here that there 90 need be no fixed number of cards to a suit, except that there should be at least nine since the cards are played one to an inning, and a game consists of nine innings at least. In the present case let us consider all the 95 cards that are shown in the drawing marked St. Louis (eleven in all) as constituting one suit. Then each suit in the pack would have to contain eleven cards as all the suits should contain the same number of cards, and a 100 game played with such a pack could continue to eleven innings if not concluded in nine.

The object of the game and the method of playing it can be more clearly explained 105 by assuming that a game is being played. We will assume that a full pack of cards or "deck" contains eight suits representing the eight teams in either the American or National Baseball Leagues, and that only two 110 players are going to play. Obviously all the suits except two must be thrown out un-

less each player represents more than one club. Let the players represent the St. Louis and Chicago baseball teams respectively. Then the cards are shuffled and dealt alternately one to each player until the cards are exhausted, which gives each player eleven cards if there are that many in a suit. Let it be understood at this point that the object of the game is to score runs, which is done by taking in, as "tricks," the cards having a "run" or run-scoring value. By "run" value is meant a value corresponding to the value of the same play in a regular game. For instance, cards 7, 8, 9, 15 and 10, having values of a base-hit, two base-hit, three base-hit, and home-run respectively, are such as are most likely to mature into runs in a regular game, so they have "run" values and when taken home in 20 a trick count a run for the player taking them if they represent his team. We will continue with the play; the cards have been dealt and one of the players leads, or plays the first card. Suppose he plays a home-run for the St. Louis team which he represents. Now this is a card of high value and the only cards that his opponent can play that will overcome it and take the trick are those which are marked "Out" such 25 as card 1. These cards have run-presenting values. However, it must be a card of the same suit as was led, *i. e.* "St. Louis" card. In other words he must follow suit or he cannot take the trick with any card. If 30 after the St. Louis representative plays the home-run card, his Chicago opponent plays a St. Louis card of lesser value (a two-base hit or foul, or in short any card other than one marked "Out") then the St. Louis 35 player takes the trick and scores a run in that inning. He then leads another card, a base-hit, for example. Now if the Chicago player can play a two base-hit or higher card (of the same suit) he takes the trick. 40 If the suit is the same as he (the Chicago player) represents then he scores a run for each of the run cards, or two in all; if it is the St. Louis suit then neither scores. This is followed for nine innings, or until nine 45 cards have been played by each player, then the player who has scored the highest number of runs wins the game. If they are tied they continue to play the cards in their hands until one wins. Should the cards be 50 exhausted before either has a greater number of runs then they are shuffled and dealt again, and play continues.

Let it be borne in mind that runs can only be scored by taking in "run" cards of the 55 same suit that the player who takes the trick represents. In determining to whom a trick belongs the following order of value from greatest down, is adhered to: home run, three base-hit, two base-hit, base-hit, ball four, ball three (when used), ball two,

ball one (when used), error, strike three, strike two, strike one (when used), foul, etc. Card 1 marked Pitcher and all other cards that contain the word "Out" will take any other card of the same suit, but they 70 have no "run" value, their purpose being to shut off runs. When cards of "run" value and of the same suit are played the player who plays the card of highest value scores a run for every such "run" card played, provided they represent the same suit or team that he represents; if taken by a player representing a different suit or team nobody 75 scores.

It might be mentioned that the number 80 of cards to a suit is immaterial since they do not all have to be used, but it is advisable to have at least nine so that a full game of nine innings, as already explained, can be played without redealing the cards.

Obviously the invention may be modified 85 without departing from the spirit of the same.

Having described my invention what I 90 claim is:

1. In a pack of cards comprising a series of suits, a suitable number of cards in each suit, said cards being horizontally divided into halves, the halves being similarly marked in opposing relation, one of said 95 markings being adjacent the outer edge of each half of the card, another being disposed along the left hand margin of each half of said card when the half is in its normal position, the former marking designating the value of the card, the latter designating the denomination of the suit, said first mentioned marking being supplemented by an abbreviation disposed along the margin above the marking giving the denomination, some of said cards being further marked by the word "Out" or its equivalent, substantially as set forth.

2. In a pack of cards comprising a series of suits, a suitable number of cards in each 110 suit, said cards being horizontally divided into halves, the halves being similarly marked in opposing relation, one of said markings being adjacent the outer edge of each half of the card, said markings designating the value of the card corresponding to the value of a play incident to a ball game, all of the cards in a suit having different values, all the cards of each suit having corresponding values, markings disposed along the left hand margin of each half when that half is right side up, said markings designating the denomination of the suit, and the first mentioned markings being supplemented by an abbreviation disposed above the denominational markings.

3. In a pack of cards comprising a series of suits, a suitable number of cards in each suit, said cards having markings adjacent the upper narrow edge of the card, further 120

- markings being disposed along the left hand margin of each card when the card is held upright, the former marking designating the value of the card, the latter designating 5 the denomination of the suit, said first mentioned marking being supplemental by an abbreviation disposed along the margin above the marking giving the denomination.
- 10 4. A playing-card being provided with a suitable marking along one edge of the card, a second marking along one edge of the card, a second marking disposed along an edge at right angles to the first mentioned edge, the one marking designating the value of the card, the other designating the denomination of the suit to which said card belongs, the former marking being supplemental by an abbreviation placed in the 15 corner of the card between the two marginal markings.
- 20 5. In a pack of cards comprising a series of suits, a suitable number of cards in each suit, said cards being divided in halves, the halves being similarly marked in opposing relation, one of said markings being adjacent the outer edge of each half of the card, another being disposed along the left hand margin of each half of said card when the half is in its normal position, the 25 former marking designating the value of the card, the latter designating the denomination of the suit, said first mentioned marking being supplemental by an abbreviation disposed along the margin above the marking giving the denomination. 30

In testimony whereof I affix my signature, in presence of two witnesses.

THEODOR NORPOTH.
